UNITED STATES PATENT OFFICE.

CLINTON O. HARRINGTON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

CIRCUIT-CONTROLLER.

1,117,376.

Specification of Letters Patent.

Patented Nov. 17, 1914.

Original application filed December 28, 1912, Serial No. 739,037. Divided and this application filed December 11, 1913. Serial No. 805,974.

To all whom it may concern:

Be it known that I, CLINTON O. HARRINGTON, a citizen of the United States, residing at Edgewood borough, in the county of Allegheny and State of Pennsylvania, have invented certain new and useful Improvements in Circuit-Controllers, of which the following is a specification.

My invention relates to circuit controllers.

10 Circuit controllers embodying my invention are particularly adapted for use in connection with electric bells, but they are not limited to this particular adaptation.

15 The present application is a division of my copending application filed December 28, 1912, Serial No. 739,037, for electric bells.

20 I will describe one form of circuit controller embodying my invention, showing its application to an electric bell of the solenoid and plunger type, and will then point out the novel features thereof in claims.

25 In the accompanying drawings, Figure 1 is a view showing one form of electric bell having applied thereto one form of circuit controller embodying my invention. Fig. 2 is a view showing in side elevation, partly sectioned, the bell shown in Fig. 1. Fig. 3 is a sectional view on the line 3—3 of Fig.

30 Fig. 4 is an end view of the circuit controller shown in Fig. 1. Fig. 5 is a view showing in detail a portion of the circuit controller shown in the preceding views.

35 Fig. 6 is a view showing a bed of electro-conductive material forming part of the circuit controller shown in the preceding views. Fig. 7 is a diagrammatic view showing one arrangement of the electric circuit for the control of the bell shown in the preceding views.

40 Similar reference characters refer to similar parts in each of the several views.

Referring first to Figs. 1 and 2 of the drawings, 10 is a casting which carries a bell and a bell-operating mechanism, and which may be mounted upon any suitable support; for example, it may be mounted at the top of an iron post to which it may be rigidly fixed by means of a screw 11. This casting 10 is provided with an inclined bed 12 upon which rests the bell-operating mechanism and a circuit controller 40. Secured to the casting 10 by means of screws

15, is a gong bracket 14 to which a gong 13 is fixed by means of a screw 16. The gong 13 and the operating mechanism and circuit controller are protected by means of a hood 21 which is pivotally mounted on the casting 10 by a screw 22 so that it may be swung into and out of protecting position. 60

The bell-operating mechanism and circuit controller are carried by a mechanism bracket 17, which rests upon the bed 12 and is removably secured thereto by means of a screw 15 and one or more rivets 16, in the 65 manner described in my co-pending application of which this application is a division.

The left-hand end (as viewed in Fig. 1) of the bracket 17 is bent upwardly at substantially a right-angle to form a plate 27. A second upright plate 28, which also forms part of the bracket 17, is provided by making two longitudinal slits extending into the bracket from the right-hand end (as viewed 75 in Fig. 1) and by bending the middle or tongue portion upwardly at right angles. This leaves two side strips 29 (only one of which is shown in Fig. 1, but both of which appear in Fig. 4), and these strips are bent 80 upwardly as shown in Fig. 1 to form a support for the circuit controller.

Mounted in suitable holes in the plates 27 and 28 is a plunger tube 18 (preferably of brass) which forms the core of a solenoid 85 30. The left-hand end of the tube 18 is slightly spun over, and the rim thus formed is held firmly against the plate 27 by a plate 59, which latter is secured to the plate 27 by screws 39. It will thus be seen that the 90 tube 18 is held firmly in place in the bracket 17. The shape of the plunger tube 18 is preferably as shown in Fig. 3, from which it will be seen that this tube is provided with three slots or raceways 31, 32 and 33 in 95 each of which are two balls 34. A plunger 19 of iron is located in the plunger tube 18 and is mounted on the balls 34 so that it may reciprocate in the tube with practically no friction. The tube 18 is preferably mounted 100 substantially parallel to the bed 12, so that the tube is therefore inclined between the horizontal and the vertical. The angle of inclination from the horizontal is preferably only slightly more than sufficient to allow 105 the plunger to roll downwardly due to the

force of gravity when not acted upon by the solenoid. The movements of the balls 34 are limited by stops 35, 36 and 37 located in the raceways, which stops as here shown are 5 pieces of metal of suitable shape secured in the race-ways by rivets 51. The plunger 19 is provided with a tapper 20 which is adapted to strike the gong 13, and which as here shown is in the form of an enlarged 10 head formed on the end of a stud 50 which is screwed into the end of the plunger. The reciprocation of the plunger 19 is limited in one direction by the engagement of the tapper 20 with the gong and in the other direction by the engagement of the right-hand 15 face of the tapper head 20 with a diaphragm 38. This diaphragm is, as here shown, formed from a sheet of thin metal which is slightly bowed outwardly and is secured to 20 the front plate 27 by the screws 39. This diaphragm serves as a stop for the moving parts and also serves to cause a slight rebound of the plunger and tapper as the latter reach their lowest position, thereby caus- 25 ing a quicker and smoother action of the bell and also reducing the energy required to operate the bell.

The circuit for the solenoid 30 is controlled by the circuit controller 40 embodying my invention and which I will now describe.

Referring to Figs. 1, 4, 5 and 6, a block 41 of insulating material is mounted on the upturned ends of strips 29 by means of bolts 35 55. This block is provided with a rectangular hole 60 (see Fig. 4) in which a supporting trough 61 is mounted. This trough, as shown best in Fig. 4, comprises a bottom and two side pieces; the front ends of the 40 bottom and sides of this trough are flared outwardly and the flanges thus formed rest against the left-hand face of block 41, as viewed in Fig. 1. Resting in the trough 61 is a block or bed 42 of electroconductive 45 material, preferably graphite, which block or bed is shown more clearly in Fig. 6, from which it will be seen that the upper surface is provided with a concave recess 48 cylindrical in form. 62 and 63 are side pieces 50 located in the trough 61 and one on each side of the block 42, which side pieces and the trough 61 and block 42 are all held securely together by means of screws 64, one of which serves as a terminal post to which 55 a conductor 65 is secured. The front ends of the side plates 62 and 63 rest against the right-hand face of the block 41 as viewed in Fig. 1, hence it will be seen that because of the flanges on the trough 61 and the side 60 plates 62 and 63, the trough, side plates, and block 42 are securely fixed to the block 41. 43 is a hollow cylindrical member or tube of electro-conductive material, such as brass, which fits the concave recess in block 65 42 and is adapted to reciprocate therein.

The radius of curvature of the member 43 is substantially the same as that of recess 48. As shown more clearly in Fig. 5, the left-hand end of the member 43 is spun over inwardly to form an inwardly-projecting 70 flange, which is clamped between two blocks of insulating material 57 and 58. One of these blocks 57 comprises a head portion which fits inside the member 43 and a shank portion which projects through the end of the member and is threaded; the other block 58 is provided with a threaded hole to screw on the shank of block 57. 44 is a stud one end of which screws into the end of plunger 19, and is held from turning therein by a 80 rivet 23, and the other end of which is reduced in diameter and is threaded. A head 45 rests against the shoulder formed by the reduced portion and is held tightly against this shoulder by a nut 66. The stud 44 passes through a hole in block 57, but the head 45 cannot pass through this hole. When the plunger 19 is rolled upwardly from the position shown in Fig. 1, the head 45 strikes the block 57 when the tapper 20 is about a 90 quarter of an inch from the gong, so the tube 43 is then moved to the left about a quarter of an inch. As the plunger returns, it strikes the block 58 when about a quarter of an inch from the lowest point of its 95 stroke, so the tube 43 is then moved back to the position shown in the drawing. 46 is a roller of conducting material mounted on one end of a suitable spring 67, the other end of which is fixed to the block 41. This roller 100 is so located as to make contact with the cylindrical surface of the member 43 when the latter is in the position shown in the drawing, but that when the member 43 is moved to the left, as hereinbefore explained, 105 it moves out of contact with the roller 46.

The operation of the bell and circuit controller is as follows: Referring to Fig. 7, the solenoid 30 is provided with a circuit which includes in series a source of current 47, the graphite block 42, the cylindrical member 43, the roller 46 and a circuit controller 70. When circuit controller 70 is closed, the solenoid 30 is energized and draws the plunger 19 upwardly so that the tapper 20 strikes the 110 gong. Just before the tapper 20 reaches the gong the head 45 moves the member 43 out of contact with roller 46 thereby breaking the circuit through the solenoid 30. The momentum of the plunger is, however, sufficient to carry it on until the tapper strikes the gong. The plunger 19 then returns by gravity to the position shown in Fig. 1. Just before it reaches this position the right-hand end of the plunger engages with 125 the block 58, moving the member 43 again to the position shown in the drawing, so that it is then in engagement with roller 46; the circuit through the solenoid 30 is then again closed and the operation is repeated. The 130

reciprocation of the member 43 on the graphite 42 causes the surface of each of these members to be maintained in a smooth and shining condition, thereby providing excellent electrical contact between the two. Furthermore, in practice I have found that the member 43 is rotated slowly around its longitudinal axis, thereby constantly presenting a new surface to the graphite 42 and to the roller 46; this produces equal wear on all parts of the cylindrical member 43, thereby maintaining the latter symmetrical in shape, and it also results in excellent electrical contact between the member 43 and the roller 46 because the entire surface of the member 43 is kept smooth and shining by the graphite.

The bell-operating mechanism and circuit controller 40 are protected by a cover 49 which is secured to the edges of the bed 12 in any suitable manner.

Although I have herein shown and described only one form of circuit controller embodying my invention, it is understood that various changes and modifications may be made therein within the scope of the appended claims without departing from the spirit and scope of my invention, and although I have shown and described a particular form of electric bell having applied thereto a circuit controller embodying my invention, it is understood that a circuit controller embodying my invention may be applied to other forms of electric bells, and that it may be applied to kinds of apparatus other than electric bells.

I do not make any claim in this application for the location of the slots or raceways 31, 32 and 33 in the tube 18, this being the subject-matter of an application filed by Charles W. Dunham on February 4, 1914, Serial No. 816,540, for electric bells.

Having thus described my invention, what I claim is:

45 1. A circuit controller comprising a fixed member; a second member movable in two paths with relation to, but constantly in contact with, said fixed member; a third member located in position for contact with said second member, the movement of said second member in one path being such that it moves into and out of contact with the third member, and the movement of said second member in the other path being such that the portion of the surface of the second member which is at times in contact with the third member rubs at other times on the surface of the fixed member, whereby the surface of the second member which contacts with the third member is kept clean.

50 2. A circuit controller comprising a cylindrically concaved bed of electro-conductive material, a cylindrical member of electro-conductive material located in said bed and having substantially the same radius of

curvature as that of the bed, said member being adapted to reciprocate in said bed and also to rotate on its longitudinal axis in said bed, and a contacting member mounted in position for contact with the cylindrical surface of said cylindrical member; the reciprocation of said cylindrical member being such that the member moves into and out of contact with said contacting member, and the rotation of the cylindrical member being such that the surface of the member which at times makes contact with the contacting member rubs at other times on the bed whereby said surface is kept clean.

55 3. A circuit controller comprising a cylindrically concaved bed of graphite, a cylindrical member of electro-conductive material located in said bed and having substantially the same radius of curvature as that of the bed, said member being adapted to reciprocate in said bed and also to rotate on its longitudinal axis in said bed, and a contacting member mounted in position for contact with the cylindrical surface of said cylindrical member; the reciprocation of said cylindrical member being such that the member moves into and out of contact with said contacting member, and the rotation of the cylindrical member being such that the surface of the member which at times makes contact with the contacting member rubs at other times on the bed whereby said surface is kept clean.

60 4. A circuit controller comprising a cylindrically concaved bed of electro-conductive material, a cylindrical member of electro-conductive material located in said bed and having substantially the same radius of curvature as that of the bed, said member being adapted to reciprocate in said bed and also to rotate on its longitudinal axis in said bed, and a roller of electro-conductive material mounted in position for contact with the cylindrical surface of said cylindrical member, the reciprocation of said member being such that the member moves into and out of contact with said roller.

65 5. A circuit controller comprising a cylindrically concaved bed of electro-conductive material, a cylindrical member of electro-conductive material located in said bed and having substantially the same radius of curvature as that of the bed, said member being adapted to reciprocate in said bed and also to rotate on its longitudinal axis in said bed, a roller of electro-conductive material, and resilient means for mounting said roller in position for contact with the cylindrical surface of the cylindrical member, the reciprocation of said cylindrical member being such that the member moves into and out of contact with the roller.

70 6. A circuit controller comprising a bed of electro-conductive material, a member of

5 electro-conductive material adapted to reciprocate on said bed, and a contact mounted in position for engagement with said member, the reciprocation of said member being such that the member moves into and out of engagement with said contact; and said bed, member and contact being included in an electric circuit.

7. A circuit controller comprising a fixed 10 member, a second member movable with relation to but constantly in contact with said fixed member, a third member located in

position for contact with the second member, the movement of the second member being such that it moves into and out of contact with the third member; said members all being of electro-conductive material and all being included in an electric circuit. 15

In testimony whereof I affix my signature in presence of two witnesses.

CLINTON O. HARRINGTON.
